UNITED STATES PATENT OFFICE.

CHARLES F. SPARKS, OF ST. LOUIS, MISSOURI.

METHOD AND APPARATUS FOR SEWING BAGS AND OTHER ARTICLES.

Application filed June 10, 1925. Serial No. 36,084.

This invention relates to the manufacture of bags and with regard to certain more specific features to means for sewing lateral and longitudinal seams in material to form a bag.

Among the several objects of the invention may be noted the provision of improved means for reducing the number of operations required in bag manufacture by 10 making practicable a combination of automatic sewing machines with other relatively higher speed apparatus such as printing, cutting and folding machinery such as is ordinarily used on bag fabric; said means 15 being adapted to permit said automatic sewing machines to form a relatively short stitch when the above named combination of sewing, printing, cutting and folding elements is used; and the provision of simplified and improved apparatus for accomplishing the above ends which shall be subjected to low speeds and slight wear and which shall subject the automatic sewing machines to low speeds and slight wear 20 although said apparatus is turning out sewed bags at a high rate of speed.

The invention accordingly comprises the features of construction, combinations of elements, and arrangements of parts which 30 are exemplified in the structure hereinafter described and the scope of the application of which will be indicated in the following claims.

In the accompanying drawings, in which 35 is shown one of various possible embodiments of this invention,

Fig. 1 is a perspective view of the machine taken from the left front and shows certain parts broken away;

40 Fig. 2 is a top plan view of the machine with parts broken away;

Fig. 3 is a section taken on line 3—3 of Fig. 2 and shows a lateral sewing machine and drive therefor;

45 Fig. 4 is a fragmentary perspective view taken from the left side of the machine, and shows a rotating sewing machine and part of the take-off mechanism;

50 Fig. 5 is a developed view of the barrel cam slot showing various positions of a lateral sewing machine therewith;

Fig. 6 shows a sewed bag previous to turning it rough side in;

Fig. 7 is a fragmentary perspective taken from the right side of the machine;

Fig. 8 is a fragmentary section taken on the line 8—8 of Fig. 2;

Fig. 9 is a section taken on line 9—9 of Fig. 2 showing the details of the rotating-sewing-machine drive in closed clutch position;

Fig. 10 is a right side elevation of the driving mechanism for the machine; taken on the line 10—10 of Fig. 2;

Fig. 11 is a section taken on the line 11—11 of Fig. 2 showing the epicyclic gear train for driving a gaining gear;

Fig. 12 is a fragmentary vertical section taken from the right side showing a feeding mechanism in mid-position;

Fig. 13 is a view similar to Fig. 12 showing the feeding mechanism as it takes a piece of cloth;

Fig. 14 is a view similar to Fig. 12 showing the feeding mechanism as cloth is fed to a platen;

Figs. 15 and 16 are rear and side elevations of a feeder plate showing a bag blank thereon;

Fig. 17 is an enlarged detail of the grab-hook frame taken from the right and rear thereof;

Fig. 18 is a vertical section taken on the line 18—18 of Fig. 17;

Fig. 19 is an ideal section taken on the line 19—19 of Fig. 2;

Fig. 20 is an enlarged sectional detail showing a rotating sewing machine sewing its overhanging cloth;

Fig. 21 is a vertical sectional view of the platen receiving means;

Fig. 22 is a fragmentary sectional detail of a platen switch;

Fig. 23 is a sectional view of a crown clutch engagement between shafts of Fig. 22;

Fig. 24 is a front elevation of the take-off apparatus;

Fig. 25 is a section taken on the line 25—25 of Fig. 24 and shows an alternate position; and

Fig. 26 is an enlarged sectional detail of

the platen receiving mechanism shown in Fig. 21.

Similar reference characters indicate corresponding parts throughout the several views of the drawings.

Preliminary.

It is proposed to show in this specification, a means for receiving a piece of material 10 folded once upon itself; means for sewing a seam longitudinally of, and opposite the folded side of the piece, the direction of said sewing operation taking place at right angles to the direction of motion of the piece 15 of material; means for sewing a seam at right angles to said seam at one end of the folded piece, said last named sewing operation taking place parallel to the direction of motion of the material but at a lower 20 rate of speed with respect to the piece than the piece has with respect to an external motionless reference frame; and means for ejecting the piece when the seaming operations have been completed.

25

General.

The material, as received by the machine to be described, is cut into pieces twice the size of a bag and folded upon itself along 30 a line 1 (Fig. 6). This operation is performed by a separate machine. The line 1 forms one longitudinal side edge of the bag and, of course, requires no sewing. It is 35 proposed to stitch in the longitudinal seam 3, which forms the other side edge of the bag, and also to stitch in the lateral lower edge seam 5. The upper edge 7 of the folded material is left open and hence a turned bag is formed.

40 The machine herein contemplated turns out a bag such as is illustrated in Fig. 6. The bag is made with its inside out and must have its inside properly reversed by 45 a subsequent process. The material may have been printed before arriving at the present machine.

Frame-work.

50 Referring now more particularly to Figs. 1, 2, 4 and 7, there is illustrated at F a framework for carrying the various members of the machine. The framework F comprises corner uprights 9 and lateral members 11 fastened thereto. Struts 13 properly brace the frame as well as a horizontal upper member 15.

Two vertical columns 17 and 19 serve as 55 mounts for the main shaft of the machine. The column 17 is located at the left-hand 60 side of the machine and the column 19 at the right-hand side thereof. Minor frame members serving mere positioning purposes for cams and the like will be described in 65 proper order later.

Main shaft M.

The main shaft M, Figs. 1, 2 and 7, is held tightly and non-rotatably in bearings 70 21 and 23. The bearings 21 and 23 are fastened to the upright columns 17 and 19 respectively.

Platen frame PF.

The platen frame PF, (Figs. 1, 2, 7, 10, 11, 19 and 21) comprises several important 75 elements. Its right end comprises a spider wheel 25 rotatably borne on the main shaft M. Permanently fastened to the wheel 25 is a spur gear 27 which is used to drive the 80 platen frame.

The left end of the platen frame comprises a four-armed spider 29 (Fig. 19) which is 85 rotatably mounted on said main shaft M by means of a bearing 32. The wheel 25 and spider 29 rotate together. They are fastened, one to the other, by means of four cross-members or rails 31 (Figs. 1, 2, 3, 7, 10, 11 and 19). The rails are bolted to the 90 front of the arms of spider 29 and to the front of anchor plates on the spokes of the wheel 25. They have functions which will be described later.

Rearwardly of the spider arms are bolted angle irons 33 (four in number) parallel to 95 the said rails. These irons serve to cooperate with a sewing machine head mounted on said rails as will be described.

The point to be made here is that the wheel 25, gear 27 thereon, the spider 29, cross 100 rails 31 and angle irons 33 are rotatable as a unit. This unit is the platen frame PF.

Drive for platen frame PF.

This is best shown in Figs. 1, 2 and 7. 105 Mounted above the machine is a motor or other prime mover PM. A speed reducing chain drive 35 connects the motor PM with a clutch 37 on a line shaft 39. The shaft 39 is borne on the top of the frame F by means of bearings 41. On the right-side upright 19 is bolted a bearing block 42. This bearing block 42 rotatably mounts a jack shaft 43. The jack shaft 43 is connected 110 with the line shaft 39 by means of a chain drive 44 which steps down speed from the shaft 39 to the shaft 43.

Referring now to Figs. 2, 10 and 11 it 115 may be seen that the jack shaft 43 is provided with a pinion 45 which is adapted to mesh with the spur gear 27 fastened to the platen frame. Hence by causing the motor PM to function, the platen frame may be rotated. The frame rotates clockwise when viewed from the right-hand side of the machine.

Platens P.

In Figs. 1, 2 and 7 are also shown the 120 platens for carrying the work to be sewed.

130

There are four platens P arranged at ninety degree intervals. They each comprise an arc shaped piece of sheet metal, preferably. They are arced over the said rails 31 and braced thereto by side plates 47 and arms 49 (Fig. 7).

The platens have one edge, the edge which cooperates with the longitudinally open side of the bag material, bent over to form a lip 51. This lip is flatly formed with regard to the substantially radial leg 53 of said angle iron 33. (Figs. 1, 2, 3 and 21). A narrow slot 55 is left between the lip and the leg 53 for purposes of seaming by means of laterally traveling sewing machines LM (Figs. 1, 3 and 7). The sewing machines LM travel on the rails over which the platens are arced. Their heels 59 travel in under the leg 53 and the lip 51, (Fig. 3) and their necks arch over the angle iron 33 to permit the needles thereof to cooperate with the heel mechanism at the slot 55 as the sewing machines travel laterally on the platen frame. Means for holding the bag material on the platen frame and across the slot 53 will be described.

Cross drive for lateral sewing machines.

It is intended that each lateral sewing machine LM, shall travel the complete length of a platen and return during one revolution of the platen frame. Of course the platens rotate with the frame. During their travel said machine shall complete the longitudinal seam of a bag. The seam of course will be made at the slot 53 over which the unseamed edges of the folded material will extend. The bag is to be removed from the platen at the rear of the machine when the lateral sewing machine is at the right of the platen frame, having finished its sewing operation. The sewing machine is to return after the bag has been removed and have its sewing head inoperable upon the return passage. This arrangement of operations holds for each of the four platens, and each of the four lateral sewing machines cooperating therewith, respectively. The parts embodying the above contemplated action are as follows:

50 A barrel cam BC is non-rotatably fastened to the main shaft M. It comprises a series of flat faced wheels upon which are mounted the cam track T in a more or less helical fashion. The developed view of this track is shown in Fig. 5. The zero degree point on the track is placed at the left forward side of the barrel. The track is of course endless when wrapped on its barrel. The degrees marked on the track T in Fig. 5 represents degrees of rotation of the platen frame starting horizontally at the front of the machine. The relative positions of sewing machine heads are shown therewith.

Fig. 3 shows the mounting of a lateral

sewing machine on a cross track 31. Rollers 61 cooperating with vertical and lateral lips of the track 31 guide the machine along the cross track or rail 31. The construction is such that the sewing machine cannot fall away from the cross rail 31 in any position 70 of said rail during rotation of the platen frame of which the rail is a member. The rollers are rotatably fastened to a flat plate 63.

On the plate 63 is mounted one of the 75 lateral sewing machines LM and drive therefor. The driving gears are located between two plates 65 mounted vertically on said plate 63 (Fig. 3). They drive the sewing machine shaft 67 which operates the sewing 80 machine parts by means of an eccentric 69. The sewing machine head per se is conventionally operable.

On the outside rear plate 65 is rotatably mounted a follower roller 71 adapted to fit 85 and follow in the cam track or groove T.

Hence, upon rotating the platen frame as described, the lateral sewing machines are caused, by means of the barrel cam and followers, to move laterally along their rails. 90 The velocities, acceleration and timing of the lateral sewing machines may obviously be controlled by proper pitching of the cam track T on its cylinder. Hence correct design, and accurate control, of the motions of 95 the four machines may be had with the use of few parts. Each machine performs its proper functions in order, as its follower comes to given points on the barrel cam. This construction results in the sewing units 100 being forced to work in perfect conjunction with one another.

The gearing for making the lateral sewing machine needles reciprocate properly is best shown in Figs. 2 and 3. Said gearing is 105 mounted between the plates 65. In Fig. 2 parts are broken away to show this gearing.

For each of the four platens, a rack 73 is mounted laterally on the platen frame, parallel to the said rails 31. This rack 73 110 passes under the tail 75 of the lateral sewing machine LM. This rack 73 is stationary with respect to the platen frame and revolves with it.

Mounted between one of the brace plates 115 65 and an auxiliary brace plate 77 is a rotatable shaft 79 carrying fast thereto a pinion 81 which meshes with said rack 73. The shaft 79 also carries fast thereto a larger gear 83 which meshes with a pinion 85 made 120 fast on a secondary rotatable shaft 87 mounted between the said brace plates 65. Another larger gear 89 is loosely held on said shaft 87 between a collar 91 and a ratchet 93. The collars and ratchet are 125 made fast to the shaft 87. The ratchet is adapted to drive the large gear 89 by means of a pawl 95 spring pressed toward its driv-

ing ratchet. The pawl 95 is permanently pinned to the side of gear 89.

The gear 89 drives a pinion 97 which is fast on the said sewing machine shaft 67. 5 The shaft 97 is borne between one of the plates 65 and the sewing machine, and carries the said eccentric 69 for driving the conventional sewing machine head parts.

The operation is almost obvious. As the 10 lateral sewing machine is driven along its rail to the right by the said barrel cam BC and the cooperating follower 71, the pinion 81 meshing with the stationary rack 73 is rotated counter-clockwise. Hence the gear 15 83 rotates counter-clockwise. The gear 83 causes the pinion 85 to rotate clockwise and hence the ratchet 93 rotates clockwise and drives the large gear 89 clockwise by means 20 of the spring pressed pawl 95. The large gear 95 drives the pinion 97 counter-clockwise and hence the eccentric is made to operate the needle mechanism of the sewing machine head. The result is, that as the 25 lateral sewing machine is driven to the right of the machine, its own motion causes its sewing elements to become operable to sew a piece of material stretched across the slot 55. The advantage of this fact is that the rate of reciprocation of the needle, (hence 30 the rate of stitching), is always proportional to the displacement of the machine and no matter how the velocity of the sewing machine is varied due to machine design requirements, a constant length of stitch is 35 obtained.

It is to be understood that in designing this machine the pitch of the cam track T is to be arranged, preferably, to give low accelerations to the lateral sewing machines 40 at the beginning and end of their sewing operations and maximum velocity therebetween. This reduces accelerating strains.

When the track T of the barrel cam brings the lateral sewing machine back to 45 the left end of its track, the drive to the sewing machine reverses its action up to the ratchet and pawl mechanism from whence no motion is obviously transmitted to the sewing machine head mechanism, and the 50 needle is inoperable on the return of the sewing machine over its rail. It is to be noted that there are used four lateral sewing machines, one for each platen.

Some of the advantages of the described 55 drive for the lateral sewing machines have been enumerated. Others are that there are no engaging and disengaging racks or gears employed for reversing the travel of the sewing machines. Thus great multiplicity 60 of parts is avoided and the timing of the device is made positive. Each lateral sewing machine functions exactly as the others.

Power required to drive the machine is 65 cut to a minimum and is all taken from a single source (see motor PM).

The rotating sewing machines RM.

These machines are illustrated in Figs. 1, 2, 8 and 9. They are adapted to sew the end seam of the bag. The folded bag blanks 70 are fed on their respective platens with the bottom slightly overhanging the left edge of the platen. This overhanging edge 60 (Fig. 20) is the part in which the rotating sewing machines RM sew their seams. It 75 is about one-half inch in width. In Fig. 20 the overhang 60 is exaggerated.

Spider S.

The machines RM are mounted at the 80 ends of the radial legs 99 of a three legged spider S. The top edges of their sewing plates are made flush with the platen surfaces, that is they are at the same radius (Figs. 8 and 20). The legs 99 are arranged 85 at 120 intervals and are bolted to a common central hub plate 101. The bolts which hold the legs 99 to the hub plate 101 also hold a gaining gear 103 to said hub and consequently to said spider. The spider and gear 90 rotate as a unit on the main shaft M, the hub of the gear 103 acting as a bearing. The rotation of the spider S, as will be explained, is made to take place in the same direction 95 as that of the platen frame but at a faster rate. Therefore their frames must be independent of one another. However, the spider S depends for its motion upon the motion of the platen frame PF.

Drive for rotating spider S.

Fastened non-rotatably to the main shaft 100 M (Figs. 2, 10 and 11) is a relatively large fixed sun gear 107.

Rotatably mounted on the wheel 25 of the 105 rotating platen frame PF are two meshing pinions 109 and 111. The pinion 109 is a planet gear meshing with the sun gear 107 and the gear 111 receives its motion from the 110 said planet gear 109. The gear 109 is caused to rotate as it travels around the stationary gear 107, that is, when the platen to which 115 said gear 109 is fastened, revolves. Relative rotative motion is transmitted to gear 111 by means of the rotation of the platen frame 115 PF. The gear 109 acts as a transmitter and an idler at once.

The gear 111 is made fast to a cross shaft 113 running longitudinally of the platen frame and rotatably borne thereon in bearings 115 and 117, to the left and right of 120 said frame respectively. The cross shaft 113 passes through the left-hand bearing 115 and overhangs the left end of the platen frame. On its overhang is located the 125 pinion 119 (Figs. 2, 4 and 8) which meshes with said independently mounted gaining gear 103. The gear 103, as stated, drives the spider S on which the three rotating sewing machines RM are mounted.

The gear ratios of the gears 107, 109, 111, 119 and 103 are arranged so that one operative turn of the platen frame PF, causes said gears by means of their epicyclic action to turn the gaining gear and spider there-with one and one-third turns in the same direction. Hence a ninety degree movement of the platen frame produces a 120 degree movement of the spider S and the 10 sewing machines thereon.

It is evident from the above description that if the rotating sewing machines have a higher peripheral velocity than the platens, that they can be made to perform a sewing 15 operation on the said overhanging edge of material in so far as the machines have a relative velocity thereto. This relative velocity is evidently less than the actual peripheral velocity of the bag material on the platens, 20 for any relative rotation of the spider S in the direction of the rotation of the platen frame PF when said rate of rotation of the spider is less than twice that of the platen frame.

25 It should be noted that by causing the epicyclic train to rotate the spider S at a slower rate than that of the platen frame, the same result as to relative speeds could be attained.

30 Now it is evident that if one of the rotative sewing machines is registered with a platen edge, so that the needle of the machine will start to sew the end seam of a bag as the platen revolves, then as the platen

35 revolves through ninety degrees, the sewing machine will revolve through 120 degrees. Hence, having four platens equally spaced, on the platen frame, and three rotating sewing machines on the spider S, there will 40 always be a rotative sewing machine registering with a platen at the starting point for a following bag. The last statement is evident when it is considered that a given point, such as say about a forward level

45 point X (see Fig. 1) in a circle of revolution, there may be present the rear edge of a platen at every ninety degree interval. The rotative sewing machines are timed to practically register with this rear edge.

50 There are only three of these machines, but since they revolve at one and one third the platen speed, there will be four of them register at said point for every platen revolution. Of course the rotative sewing machines are 55 gaining distance over the platens from this point on, and hence, may perform their sewing operations if made operative to sew. The operatives for the rotative sewing machines will be described.

60 Before proceeding the following facts should be noted.

The rotative sewing machines RM start sewing at the rear end of the platens at about a forward level point X in a circle of revolution, one after the other. The

platens subtend an arc of approximately forty-five degrees (ahead of the rear edges). At the start of a sewing operation each platen with its bag thereon lies ahead of its respective revolving sewing machine.

Now, if the platen frame revolves (180-45) degrees, or 135 degrees, a platen, having started as above described, will have its forward edge on the rear level point Y of the circle (see Fig. 7). In the meantime 75 the corresponding rotative machine has turned one and one third times 135 degrees which equals 180 degrees, or it has reached said rear level point also. It has overtaken the forty-five degree distance occupied by 80 the platen and hence has finished its sewing operation on the end seam of the bag. From this point the machine proceeds ahead of its said platen to join the next platen at the proper forward level point and at 85 the rear edge of said next platen. In the drawings the forward edges of the platens are indicated by the numeral 121, and the rear edges thereof by the numeral 123.

Drives for rotative sewing machines.

The rotative machines RM must be made to perform a sewing function and this only for the described one-half circle of advance past a platen, namely for their upper 180 95 degrees of travel from front to rear. (See Figs. 1, 2, 8 and 9.)

The machines are made to function by fastening to the left end of the main shaft M a stationary sun gear 125. This gear 125 has permanently formed therewith an operating cam 127 subtending practically a 180 degree arc over the upper half of said gear. The cam is beveled on the right sides of its ends. The exact placement of this 100 cam is slightly modified by other portions of the structure to be described but the figures given are substantially correct.

Extending rearwardly from each of the outer ends of the said three legs 99 of the 110 spider S is a drive-gear box 129 (Figs. 1, 8 and 9.)

Drive gears for each of the rotative machines RM are in said boxes 129. These gears for each box comprise two gears 131 and 133 fixed to a cross shaft 135 rotatably mounted longitudinally within the said box. The smaller gear 131 meshes with said sun gear 125 and is a planet gear therefor. The larger gear 133 meshes with a pinion 137. The pinion 137 is keyed to a hollow drive shaft 139 also rotatably mounted within said box and parallel to said cross shaft 135. The drive shaft 139 has formed on its right end a leather faced flange 141. Another leather faced flange 143 cooperates face-to-face with said flange 141. Both flanges are bored in the line with the hollow portion of the shaft 139.

A spindle 145 passes through the hollow 130

portion of the shaft 139 and the bores of the flanges. A flange 147 is permanently formed on the right end of said spindle. Between the flanges 147 and 143 is placed a conventional thrust bearing. The flange 143 is provided with drive pins 149 which slidably fit into holes in a flange 151 of the eccentric or drive shaft of the revolving machines RM.

10 The left end of the spindle 145 passes loosely through a flat clutch yoke 153 which may swing freely with the spindle 145 passing therethrough. The yoke 153 swings on a pivot rod 155 rotatably mounted in a bearing 157. The bearing is fastened to the gear box. The lower end of the rod 155 is offset and carries rotatably thereon a lower roller 159. The yoke 153 and the roller 159 may oscillate with the rod 155 as center.

15 The spindle 145 has formed on its extreme left end a head 161. A spring 163, formed loosely around the spindle 145, reacts between said head 161 and said yoke 153 when the yoke is in its Fig. 9 position.

20 The operation of the drive is as follows:

25 As the spider S revolves clockwise (Fig. 8) each gear box 129 passes around the periphery of the sun gear 125. Hence the gear 131 meshing with gear 125 is driven. The hollow shaft 139 is driven by the gear train, 131, shaft 135, gears 133 and 137.

30 When a box is in any of its lower semi-circular positions with respect to the gear 125, the cam 127 is of course not operable on the follower 159.

35 The spring 163 expands to its limit and there is no interaction between the collar or abutment 161 and the yoke 153. The 40 cam follower 159 may go to a position to the left of that shown for it in Fig. 9. Hence the spindle 145 may slip to the right and obviously permit a loose cooperation between the plates or flanges 141 and 143. 45 Hence the hollow shaft, although rotating, cannot revolve the drive pins 149. The sewing machines are not operating on the lower half of their revolution.

50 When the box 129 passes to the upper half of the circle of revolution the follower 159 is adapted to cooperate with the cam 127 (Figs. 8 and 9). Hence the follower is driven to the right and the yoke to the left. (The yoke and follower are on substantially opposite sides of the pin 155). 55 This results in the spring being driven to the left. It drives the abutment 161 to the left, whence the spindle 145 is also driven to the left and the plates 141 and 143 are made to cooperate closely at their leather faces. These plates then act as a clutch, now closed, and the clutch pins 149 are revolved to drive the flange 151 of the sewing machine drive shaft.

60 65 The spring 163 compresses when thrown

to the left and thereby is made reactive. The compressibility of the spring permits the parts of the drive to be made with large tolerances as the spring acts as a compensating element. It also compensates for 70 wear on the disc faces.

75 When the cam 127 is fastened to the top of gear 125 it is offset forwardly a slight amount to compensate for the forward reach of the follower offset.

80 From the above description it is seen that the revolving sewing machines RM are made operative only on the upper half of their swing, that is, while they are forwardly passing a platen. Hence they may sew a seam in the described overhanging edge of cloth on said platens.

85 Since the relative speeds as the machines pass their respective platens are relatively small (about fifty or sixty feet per minute while the peripheral speed of the material with the platens is about one hundred feet per minute or more) the gearing for the machines may be designed to give them a low needle reciprocating rate. The 90 advantages of this are great. It implies that material may be fed through this machine at a higher rate of speed than the heads of these sewing machines could handle ordinarily, were the relative rate with respect to said heads, the rate fed through the machine. The result is a machine of higher seaming capacity, for any given design of sewing machine head.

95 The crux of the improvements herein recited, is the fact that work traveling into and out of this machine at a high rate of speed, has a long enough travel through the machine to permit of relatively leisurely operations being performed thereon by relatively low speed sewing machinery. Low speeds of course result in little wear.

100 The particular mechanisms employed herein to bring this fact to pass, are themselves subject to slight wear and tear.

105 The mechanism for feeding bags to the platens will now be described.

Blank feeding mechanism.

110 As described, cloth or other material is folded once before feeding it to this machine. The folded piece is called a bag blank.

115 Figs. 1, and 12 to 16, show how the blank is transferred to a platen.

120 Forwardly of the machine and formed on proper braces is a feed plate 165. This plate has approximately the area of a folded bag blank and is formed in a quarter circular fashion (see Fig. 16). At intervals 125 on the lower edge 166 of the plate are formed short upturned lips 167. The lips 167 are not raised to a vertical position. Their only function is to lightly hold a bag blank in position on the feed plate. 130

The blank is laid on the feed plate by hand or machinery with its folded edge up and open lower edge down. The open lower edge is to be seamed by the said lateral sewing machines.

The feeding mechanism to be described takes the blank from its position on the feed plate and feeds it on to a platen.

Said mechanism comprises a pinion 169 borne at the right side of the machine below the main shaft M and driven by the said platen frame gear 27. The speed ratio of gear 27 and pinion 169 is 1 to 4.

Arranged on bearings at the front of the machine is a rock shaft 171 which has a crank 173 fastened to the right end thereof. A connecting rod 175 reaches from a crank pin on said pinion 169 to said crank 173. For every revolution of the platen gear 27 the rock shaft is then rocked four times through a complete cycle to be described.

Fastened to the rock shaft 171 is a frame 177 comprising two end pieces 179, a spacer piece 181 and a pivot rod 183 between said end pieces.

Fastened to said pivot rod 183 is a grab-hook frame 185 (Figs. 17 and 18). The frame is provided with permanent spring fingers 187 fastened to the forward side thereof. On the rear side of the frame and parallel thereto is held in bearings a finger shaft 189. This shaft 189 has permanently associated therewith a series of spring fingers 191 adapted normally to cooperate with the said permanent fingers 187. A coil spring 193 fastened to and around the finger shaft, and reacting on the frame 185, causes the normal engagement between the sets of fingers 191 and 187. The finger shaft overhangs the frame 185 at the right end thereof and is there provided with a finger cam 195. A trip piece 197 is adapted to cooperate with the finger cam 195 at a predetermined point in the forward travel of the finger cam, to rotate the finger shaft and separate the sets of fingers 187 and 191. This action is accomplished against the reaction of the spring 193 which returns the fingers to a cooperating position when the finger cam 195 has passed over its trip 197. The trip 197 is fastened to the machine frame F at a convenient point.

Returning to the pivot rod 183, it may be noted (Fig. 1) that it overhangs the right end of the frame 177. Fastened to said rod 183 at the overhang is a slide-rod 199.

The grab-hook frame is directly operable with the pivot rod 183 from this slide rod 199.

60 The whole frame 177 is directly operable with its shaft 171 from the crank 173.

The operative for the slide rod 199 is also borne on said shaft 171 and takes its motion from the connecting rod 175, as follows: (Figs. 1 and 12 to 14).

An independent oscillatory sleeve 201 is arranged on the shaft 171. This sleeve 171 is provided with a hook shaped arm 203 which rests on the upper surface of the connecting rod 175. Another arm 205 is provided on said sleeve 201 and is angularly placed to the front of said arm 203. In effect, the arms 203 and 205 form one kinematic link 204.

Likewise the crank 173 and frame 177 form another kinematic link 178.

The former link 204 is operable by means of the rising and falling motion of the connecting rod, while the latter link 178 is operable by the more or less reciprocating motion of said rod.

The arm 205 is provided at its outer end with a pinned slider-block 207 which encases the slide rod 199.

The frame 185 and its slide rod 199 form a third kinematic link 200.

A coil spring 209 reacting from some convenient point on the frame pulls the arm 203 down on to the connecting rod at all times.

The operation of the blank feeding mechanism is best shown in Figs. 1, and 12 to 16.

A bag blank is put on the feed plate 165 (see Figs. 15 and 16).

In Fig. 12 a platen P has just passed and received a blank. It is not shown for purposes of clarity. The pinion 169, since the platen frame gear 27 rotates counter-clockwise (viewed from the left of the machine) rotates clockwise.

The kinematic link 178, comprising crank 173 and frame 177 is rotating clockwise. This action carries the grab-hook frame 185 in a general forward or right-hand direction. From the Fig. 12 position the connecting rod 175 is descending so that the kinematic link 204 comprising arms 203 and 205 is descending henceforth for one half revolution. The result is that the slider block 207 is drawn down as the link 178 rotates clockwise.

Therefore the cooperating fingers 187 and 191 (forming grab-hooks) are rapidly moved forward of the machine to a position at the lower edge 166 of the feed plate 165 (see Fig. 13).

In reaching that position the finger cam 195 has passed over the trip 197, just prior to the time that the grab-hooks reach the cloth which overhangs notches 168 between said lips 167. The hooks are aligned with said notches.

The cam causes the hooks to open and pass their fingers 187 and 191 over and under the cloth respectively. After passing over its trip the cam of course returns to its original position under action of the spring 193. This also recloses the spring fingers of the hooks and they grip the lower

open edge of the bag blank. Since the trip is formed of spring material, return over its hooked end by the finger cam merely brushes the trip aside with no action on the grab-hooks.

The next crucial position for the feeding linkage is shown in Fig. 14. Here the pinion 169 has rotated somewhat less than 180 degrees from its Fig. 13 position.

10 This action has drawn the crank 173 from its right hand position, counter-clockwise to its left hand position. Hence the hooks with the bag blank therewith have been drawn over also.

15 Furthermore, the Fig. 14 position for the center of the slider block 207, is practically that of its Fig. 13 position so that the pivot rod 183 has passed the center of the slider block 207 in a counter-clockwise direction.

20 This has caused the slider block to turn on its fork, and due to relative motion of the link 178 with respect to the now stationary link 204 has caused the link 200 to turn clockwise to its Fig. 14 position, and hence 25 extend the hooks with their bag blank far to the left, out over a now rising platen.

The action of the hooks is to the left, while rising with the platen. The action of the hooks and the platen is timed equally 30 for a short distance in upward travel after which the rate of rise of the hooks becomes faster than that of the steadily moving platen.

35 While the hooks and platen are together the hooks deposit the blank edge on the said radial leg of the angle iron 33 which cooperates with the turned-in portion 51 of the platen. A mechanism on the angle iron, to be described, grips the cloth and it drapes 40 down over the platen edge.

45 Then the hooks accelerate upwardly away from the platen by means of the rotating action of link 200 as described and finally 50 rotate out of the way of said platen as it passes upwardly.

The link 200 pauses as the crank pin of the pinion 169 goes through the first part of its last quarter turn.

55 During the last quarter turn of the pinion, the feeding linkage returns to the Fig. 12 position, the hooks passing to the right and away from the platen over toward another waiting bag blank on the feed plate.

The withdrawal of the hooks from the 60 blank at the platen is accomplished merely by the accelerating action which, when the bag is held on the iron 33, slips the curved spring fingers of the hooks from the edge of the blank. The hooks draw upwardly 65 away from the platen.

Platen receiving means.

This mechanism is shown in Figs. 1, 21, 23 and 26. It comprises a rod 208 borne in 65 a bearing on one side of said angle iron

33. The rod is placed longitudinally of said iron and may oscillate in the said bearing. It has fastened thereto three spring fingers 211 at the right end thereof which are adapted to cooperate with the leg 53 of said angle iron under action of a spring 70 to be described. The spring fingers 211 are laterally placed in such positions so as not to interfere with the hooks of the feeding mechanism described.

75 Formed over the left end of the rod 208 is a sleeve 210, rotatably mounted thereon but not laterally slidable. This sleeve 210 carries fingers 212 similar to said fingers 211. The sleeve is normally adapted to press its fingers 212 to the iron 33 as the fingers 211 are pressed. This is done by means of the reaction of a spring 213 reacting between the iron 33 and the hollow sleeve 210 to spring turn the sleeve normally counter-clockwise when viewed from the right (see Fig. 25).

80 At the right end of the sleeve is cut a crown slot 214. A pin 216 is screwed into the rod 208 at the upper edge of this slot. There is ample play between the pin and the lower edge of the slot. The function of this construction will be explained later.

85 The rod 208 overhangs the right end of the iron and is there provided with a lever 215 (Fig. 21). This lever normally has a substantially radial position when the fingers 211 cooperate with the iron 33. It has a roller follower 217 rotatably fastened on its inner end, and a rod 219 pinned to 90 its outer end. The rod 219 passes through a guide 221 fastened to the wheel 25 of the platen frame. A spring 223 on the rod reacts between the lever 215 and said guide 221 to put the fingers 211 to a clamped position.

95 A cam 225 fastened to a convenient point on the machine frame, is adapted to cooperate with the follower 217 at a time when it is desired to raise the fingers from the 100 iron 33 for placement of a bag blank on said iron by the described feeding hooks. As the bag blank is placed on the iron the follower 217 rides over the cam 105 225, turns its lever 215, whereupon the rod 209, turns clockwise (Fig. 21) and lifts the fingers 211. The fingers 212 on the sleeve 210 are also lifted as the sleeve is reversed clockwise by the action of the pin 216 on the upper edge of slot 214 (See Fig. 23). This action takes place against the reactions of springs 213, 223 and as soon as the follower 217 has passed over the cam 225 the fingers return to their position 115 on the iron 33 but the blank is now held between them and said iron. The blank has been deposited, as described, by the feeding mechanism. (See Figs. 1, and 12 to 16).

120 To hold the rear end of a bag on the platen as the bag is fed thereto a similar 130

device is used. (Figs. 1 and 7). Here a spring return device 227 having a roller 229 operable on a cam 231 (Fig. 1) operates by means of a shaft under the rear end of the 5 platen, two T-clamps 233 which reach through slots on the platen.

As the bag blank is fed to the platen, and as the roller 217 rides over its cam 225, the roller 229 also rides over its cam 231, hence 10 raises the T-clamps 233 from the platen, and it is possible to apply the bag blank as described. As the platen frame revolves further the roller 229 leaves its cam and the T-clamps close down on the folded rear side of 15 the blank thereby holding it fast to the platen.

At this stage a lateral and a revolving sewing machine each start operating to sew their respective seams. The revolving machine 20 starts at the left-rear of the platen and the lateral machine at the left front thereof.

Platen sewing machine switch (Figs. 2, 7 and 22).

25 It is evident that the lip 51, while permitting passage of a lateral sewing machine as described would not permit passage of a gaining revolving machine, were its left end inflexible. To provide for this the lip 51 is cut away for a distance at its left end. It is cut back enough to permit passage of the sewing plate of a revolving machine. At the cut portion of the lip 51 is placed a hinged switch plate 235.

35 This plate normally rests on the sewing plate of a lateral sewing machine. A spring clip 237 holds it normally parallel to said lip 51. The switch is provided with upwardly extending pins 239 for holding the 40 plate to the bag blank. These pins do not interfere with the operation of the lateral sewing machine. It is evident that a lateral machine may sew past the switch plate as well as it could the original lip taken from the cut-out section.

45 However when a revolving sewing machine arrives at the switch, its sewing plate pushes the switch plate 235 into line with the lip 51. This is a positive action and thereupon 50 the fingers 212 on the sleeve 210 are forced upwardly from the iron 33 against the reaction of spring 213. The fingers 211 stay down on the iron 33 because of the lost motion between the sleeve 210 and the pin 216 55 of the rod 209 to which the fingers 211 are fastened.

Hence while the cloth is held down at the right side of the platen for the operation of a lateral sewing machine thereon, it 60 is raised at the left end with the switch plate for operation of a revolving machine thereon. Of course before the arrival of the 65 revolving machine at the switch, the lateral machine has traversed the switch in sewing its longitudinal seam.

After passage of a revolving machine the switch takes its normal position parallel to the lip 51, as by this time, although the sewing plate of the lateral machine is not present, the platen is headed down on the 70 rear of the machine and the switch is inverted, whereby gravity holds it horizontally against the angle in the spring clip 237. The fingers 212 return to their normal position and hold the material down on the iron 33. 75

It may be noted in Fig. 1 that a downwardly bent leaf spring 241 on the sewing plate of the revolving sewing machines guides the overhanging cloth on to the said sewing plate as the sewing machine advances along the platen edge. 80

Thread cutters.

All of the conventional sewing machine heads in this machine are equipped with 85 automatic thread cutting devices for severing the thread at the end of a seaming operation. The conventional method for making operable the thread cutter is to have a lug on the sewing machine head operable 90 by means of a linkage to move the thread cutter to cutting position. The lug cooperates with another stationary lug at the end of a seaming passage and thereby brings the cutting mechanism into play. Details 95 of one of the thread cutters are shown in the broken portion of Fig. 3. Two shear knives 243 having a pin joint 245 are pinned at a joint 247 in a vertical slot to the rear of the needle head. This pin joint 247 is on one blade. The other has a corresponding pin joint 249 joining it to a follower piece 251 which passes out of the end of the sewing plate. The follower 251 is spring held in its outward position. When the 100 sewing machine reaches the end of its seaming passage the follower 251 strikes a wedge cam 253 fastened to the platen frame which causes the follower to be pushed into the sewing plate against the reaction of its 105 spring, thereby closing and raising the shear blades to cut the thread.

The revolving sewing machines are equipped with like cutters and cams.

Take-off mechanism.

This is best shown in Figs. 2, 4, 7, 24 and 25. Between two vertical uprights at the rear of the machine and in bearings thereon is horizontally placed a rotatable 120 shaft 255. It is rotated counter-clockwise (from the right) as shown in Fig. 7, by means of a chain drive 257 from the shaft of the pinion 269. The drive gives a one to one ratio so that the shaft 255 rotates 125 four times forwardly for every revolution rearwardly of the platen frame, since the pinion rotates four times for every revolution of the plate frame as described.

The shaft 255 is provided rigidly with 130

two flat faced pulleys 259. Borne rotatably between these pulleys in bearings thereon is a shaft 261 parallel to said shaft 255.

The shaft 261 is provided, at points near each of the pulleys, with clamping plates, or springs 263, made fast to the shaft and each adapted to press against the outer surface of a pulley 259. A coil spring 262 around the shaft 261, reacting between said shaft and the left hand pulley serves to normally hold the clamping plates 263 held tightly against the pulley surfaces.

It may be noted in Fig. 2 that one of the plates is on a right-hand overhang of the shaft 261. On the left-hand overhang of said shaft is formed tightly a lever arm 265 extending substantially inwardly with respect to the periphery of one of the pulleys 259, when the clamping plates 263 are seated 20 on their pulley surfaces (Figs. 24 and 25).

A cam 267 to the left of the left-hand pulley 259 is adapted to cooperate with a roller 269 on the end of the said lever 265.

Referring to Figs. 2, 4, 24 and 25 it is evident that as the chain drive 257 rotates the shaft 255 forwardly, that the roller 269 is caused to cooperate with the cam 267 every revolution. This causes a rotation of the shaft 261 in a direction, relative to the pulleys 259, which is clockwise when viewed as in Figs. 4, and 25. Hence the plates 263 are drawn away from their pulley surfaces once every revolution. The length of the cam 267 is made such that the plates 263 are 35 made to withdraw from the pulleys 259, when they are on a rear horizontal level and open downwardly. Also said plates are again caused to approach and seat on their respective pulleys when they are on their front horizontal level and open upwardly.

Shortly, the plates 263 clamp to their pulley surfaces only during the lower half of their revolution and are drawn away from their pulley surfaces during the upper 45 half of their revolution.

Hence if a bag blank is freed by its fingers 211 and 212 and is permitted to drape from a platen at the rear of the machine hanging by said rearward T-clamps 232 (clamps 232 50 are now higher than the said fingers), then as the platen rotates downwardly at the rear, the sewed bag edge will drop in between said open plates 263 and the pulleys 259. This happens if the parts are properly synchronized. (See Figs. 2 and 25).

The complete cyclic action of the take-off mechanism is as follows:

As a platen revolves downwardly at the rear of the machine its follower wheel 217 60 strikes a cam 271 mounted on the frame (Figs. 7 and 21). This opens the fingers 211 and 212, as described for cam 225. The now sewed front edge of the bag is freed and hangs downwardly.

In the meantime the pulleys 259 have rotated to such a position that the now open clamp plates 263 are ready to receive the descending hanging edge of the bag.

As the pulleys 259 and platen rotate further the pulleys and clamps draw the bag 70 out to the rear, taking it from the platen (Fig. 25).

Soon the follower 229 of the platen reaches a cam 273 on the frame and the T-head clamps 232 free the cloth or bag (Fig. 7). 75 At this stage, the clamps 263 of the pulleys 259 have reached their rearward position. Here they open downwardly, as described. Hence the bag is dropped from the clamps 263 and clamps 232, almost simultaneously. 80 The sets of clamps 263 and 232 are almost at the same level when the bag is dropped, the former rising and the latter descending, so that the bag is dropped flatly (not on end) and a neat pile of the finished bags is formed 85 at the rear of the machine. An operator may remove the pile of bags at infrequent intervals (Fig. 2).

Complete operation.

The operation of the complete machine is as follows:

First, bag blanks are formed by cutting pieces of bag material to uniform lengths, and by folding said material longitudinally. 95 The material may be printed on the inside. Cutting, folding and printing is done on a separate machine.

From the said machines the bag blanks are fed on to the feed plate 165 of the present machine. (Figs. 15 and 16). The open edge of the blank is at the lower edge of the feed plate.

From the feed plate 165 the fingers 187 and 191, operable by means of the connecting rod 175 and associated parts, take the open edge of the blank and place said edge on the radial leg 53 of the angle iron 33. This action takes place while the platens P are moving upwardly on the forward side 110 of the platen frame PF which is revolving rearwardly.

Fingers 211 and 212 clamp said edge of the blank as described as the fingers 187 and 191 pull away from it upwardly to return for another bag blank, now on the feed plate 165. As the platen in question rises the rear folded edge of the blank approaches the rear edge of the platen and is clamped thereto by the T-clamps 233. The blank is now clamped to a platen and moving with it. It has an overhanging edge of about one-half inch extending over the left edge of the platen. See Fig. 20.

The platen switch 235 is resting flatly on its lateral sewing machine plate under the blank. See Fig. 22.

At this juncture, considering only the one

platens, the lateral and revolving sewing machines associated with the platen start sewing on the blank. See Fig. 1.

5 The lateral machine LM proceeds to the right under the influence of the barrel cam BC. Its sewing plate passes under the switch 235 and the lip 51 of the platen P. The movement of the machine causes its head to sew a seam along the line of the 10 slot 55, as described. This is the longitudinal seam of the bag opposite the fold.

At about the time of the starting of the lateral sewing machine, one of the revolving machines catches up with the left-rear corner 15 of the platen. This happens when the rear edge of the platen is at the forward level of its circle of revolution. This is due to the action of the said epicyclic train between the platen frame PF and the gaining gear 103 20 which causes the spider S of the revolving machines to gain, in distance turned, over the platen frame.

The revolving machine, as it gains the platen, has its clutch thrown in by the cam 25 127. The machine is made operable to sew through gearing from the stationary gear 125 about which it rotates. As the machine gains over the platen its leaf spring 241 feeds the overhanging edge of the blank on 30 to the sewing plate of the machine and the bottom seam of the bag is formed.

With events proceeding as described the platen revolves rearwardly through an angle of 35 135 degrees bringing the forward edge of the platen to the most rearward horizontal level of the circle of revolution. In the meantime the lateral sewing machine will have made a complete traverse of its rail to the right under influence of the stationary 40 barrel cam. It will also have automatically cut off its thread and the lateral seam will be finished.

Likewise the revolving machine will have traversed the platen edge, its spring 241 will 45 have thrown the platen switch, to permit passage of the machine on around to the next platen and the machine will have automatically cut its thread after passing the platen.

50 Thus the longitudinal and bottom seam are finished at once by the lateral and revolving machines respectively.

At about this time the fingers 211 and 212 55 open and permit the now finished bag, to drop away from the platen at said bag's sewed edge.

The sewed edge drops into the clamps of the take-off mechanism and is rotated downwardly and rearwardly. As the rear edge 60 of the platen approaches the said former position of the front edge, the T-clamps 233 open. At this juncture the clamps of the take-off mechanism open and the bag is dropped flatly. The switch plate, during 65 this procedure has been again held parallel

to the lip 51 by the spring clip 237 and the action of gravity.

As the platen proceeds beneath the machine the lateral machine is returned to its starting position at the switch plate. The 70 said barrel cam again performs this operation. The machine does not operate to sew on the return stroke for reasons stated regarding the pawl in its gearing.

The revolving machine is not operable to 75 sew after having passed a platen because of the action of the cam 127. The roller 159 passes from the cam and relieves the clutch described, whereupon the machine ceases needle operation until it overtakes the next 80 platen. The cam 127 then re-engages the clutch to operate the sewing machine.

The finished product is shown in Fig. 6. It must be turned inside out from its form there shown before it is ready for use. This 85 operation is performed by another machine.

From the above it will be seen that the several objects of the invention are attained and other advantageous results achieved.

As many modifications of the embodiments above illustrated might be made without departing from the spirit or scope of the present invention, it is intended that the above description and accompanying drawings and claims shall be interpreted as illustrative and not in a limiting sense.

I claim:

1. A method for sewing seams in material comprising moving the material at a given rate of absolute speed and sewing a 100 seam therein substantially in the direction of motion at a lesser rate of speed with respect to the material than said absolute speed of the moving material.

2. Apparatus for sewing seams in material 105 comprising means for moving the material at a given rate and means for simultaneously sewing a seam in said material substantially in the direction of motion at another rate.

3. Apparatus for sewing seams in material 110 comprising revolving platens, means for mounting material on the platens and sewing machines revolving faster than said platens and adapted to seam said material which is moving with the platens.

4. Apparatus for sewing seams in material comprising revolving platens, means for mounting material on the platens and sewing machines revolving relatively to said platens and adapted to seam said material 120 on the platens at a lesser speed than the speed of the material.

5. A method for sewing seams in material comprising moving the material at a given rate of speed, simultaneously forming a 125 seam in said material transversely of the direction of motion, and sewing a seam therein parallel to the direction of motion at a rate which differs from the first named rate,

6. Apparatus for sewing seams in material comprising revolving platens, means for mounting material on the platens and transversely movable sewing machines revolving with the platens for sewing a seam in said material, and peripherally moving sewing machines moving relatively to said platens and adapted to seam said material on the platens.
10. Apparatus for sewing seams in material comprising movable platens, means for mounting material on the platens, transversely operable means associated with the platens for sewing a seam in said material, sewing machines revolving relatively to said platens and adapted to seam said material on the platens at a different rate of speed than that of the platens.
15. The method of sewing a bag, comprising moving bag material, sewing a seam in said material laterally, of its direction of motion, and sewing a seam parallel to its direction of motion at a rate of speed less than the rate of motion of the material.
20. The method of sewing bags comprising moving bag material and simultaneously sewing right-angled seams therein, one of which seams is formed parallel to the direction of the movement of the material and at a lesser rate than said movement.
25. The method of sewing a seam comprising, moving of material and moving a sewing head at a different rate in the direction of the material movement while the seam is being formed by the sewing head.
30. Apparatus for sewing a seam comprising a movable platen adapted to carry a piece of cloth, a movable sewing head mounted in conjunction with the platen, a stationary cam, a follower for said cam adapted to move said sewing head laterally of the motion of the platen.
35. Apparatus for sewing seams in bags comprising a movable platen frame adapted to carry pieces of fabric, movable sewing heads mounted on the frame, a cam stationary with respect to the frame, followers for said cam adapted to move said last named sewing heads laterally of the motion of the frame.
40. Apparatus for sewing seams in bags comprising a rotatable frame, platens thereon adapted to carry pieces of fabric, movable sewing heads mounted on the frame, adapted to sew cloth on said platens, a stationary barrel cam arranged longitudinally of the center of the frame, followers for said cam adapted to move said heads laterally of the motion of the platen as the frame moves.
45. Apparatus for sewing seams in bags comprising a rotatable frame, platens thereon adapted to carry pieces of fabric, movable sewing heads mounted on the frame adapted to sew cloth on said platens, a stationary barrel cam arranged longitudinally of the center of the frame, followers for said cam adapted to move said heads laterally of the motion of the platen as the frame moves.
50. Apparatus for sewing seams in bags comprising a rotatable frame, platens thereon adapted to carry pieces of fabric, movable sewing heads mounted on the frame adapted to sew cloth on said platens, a stationary barrel cam arranged longitudinally of the center of the frame, followers for said cam adapted to move said heads laterally of the motion of the platen as the frame moves.
55. Apparatus for sewing seams in bags comprising a rotatable frame, platens thereon adapted to carry pieces of fabric, movable sewing heads mounted on the frame adapted to sew cloth on said platens, a stationary barrel cam arranged longitudinally of the center of the frame, followers for said cam adapted to move said heads laterally of the motion of the platen as the frame moves.
60. Apparatus for sewing seams in bags comprising a rotatable frame, platens thereon adapted to carry pieces of fabric, movable sewing heads mounted on the frame adapted to sew cloth on said platens, a stationary barrel cam arranged longitudinally of the center of the frame, followers for said cam adapted to move said heads laterally of the motion of the platen as the frame moves.
65. barrel cam arranged longitudinally of the center of the frame, followers for said cam adapted to move said heads laterally of the motion of the platen as the frame moves and means for driving said heads, said means comprising stationary racks on the frame and gear trains between said racks and said heads whereby the heads are made operable upon being driven as described.
70. 15. Apparatus for sewing seams in bags comprising a rotatable frame, platens thereon adapted to carry pieces of fabric, movable sewing heads mounted on the frame adapted to sew cloth on said platens, a stationary barrel cam arranged longitudinally of the center of the frame, followers for said cam adapted to move said heads laterally of the motion of the platen as the frame moves and means for driving said heads, said means comprising stationary racks on the frame and gear trains between said racks and said heads whereby the heads are made operable upon being driven as described, and ratchets in said trains whereby the heads are made to sew while moving in one direction only.
75. 16. Apparatus for sewing seams comprising a rotatable platen frame adapted to carry pieces of fabric, a rotatable spider driven from said frame at a relative velocity thereto, and sewing machines mounted on said spider, said machines being adapted to sew a seam in said fabric in a direction parallel to the direction of frame motion.
80. 17. Apparatus for sewing seams comprising a rotatable platen frame adapted to carry pieces of fabric, a rotatable spider driven from said frame at a relative velocity thereto, and sewing machines mounted on said spider said machines being adapted to sew a seam in said fabric in a direction parallel to the direction of frame motion at a relative velocity which is less than the absolute velocity of the pieces of fabric.
85. 18. Apparatus for sewing seams comprising a rotatable platen frame adapted to carry pieces of fabric, a rotatable spider driven from said frame at a relative velocity thereto, and sewing machines mounted on said spider, said machines being adapted to sew a seam in said fabric in a direction parallel to the direction of frame motion, movable sewing heads mounted on the frame, a cam stationary with respect to the frame, followers for said cam adapted to move said last named sewing heads laterally of the motion of the frame.
90. 19. Apparatus for sewing seams comprising a shaft, a platen frame rotatable thereon adapted to carry pieces of fabric, a spider rotatable on said shaft and driven epicyclically from said frame at a relative velocity thereto, sewing machines mounted on said spider and a stationary gear on said shaft, gear trains on said spider adapted to
95. 100. 105. 110. 115. 120. 125.

put said stationary gear and said sewing machines in driving connection whereby the sewing machines seam said pieces of fabric.

the rate of driving being proportional to the rate of travel of the sewing machine on the frame. 65

20. In a machine of the class described, the combination of a rotatable frame adapted to carry fabric to be seamed, a fixed gear, a gear train on said frame moving with the frame and relatively to said fixed gear said gear train meshing with said fixed gear and rotating, a rotatable gear on center line with said fixed gear, which rotatable gear is driven by said gear train in the direction of the frame but at a different rate of speed, a spider on said rotatable gear, sewing elements on said spider adapted to perform a seaming operation on the said fabric, said seaming operation taking place linearly at a rate which is less than the linear velocity of the fabric.

5

10

15

24. In a machine of the type described, the combination of a barrel cam, a number of platens rotating there around and a revolving frame therefor, sewing machines mounted on said frame and adapted to be moved laterally on the platen by the cam, driving gears for the sewing machines, racks formed fast to the frame parallel to the direction of motion of the machines on the frame, said racks meshing with sets of driving gears to drive the sewing machines as they travel on the frame. 70 75

20 21. In a machine of the class described the combination of a rotatable frame adapted to carry fabric to be seamed, a fixed gear, a gear train on said frame moving with the frame and relatively to said
25 fixed gear said gear train meshing with said fixed gear and rotating, a rotatable gear on center line with said fixed gear, which rotatable gear is driven by said gear train in the direction of the frame but at a different
30 rate of speed, a spider on said rotatable gear, sewing elements on said spider adapted to perform a seaming operation on the said fabric, said seaming operation taking place linearly at a rate which is less than the
35 linear velocity of the fabric, means for making the sewing elements operable to sew, said means comprising a stationary gear on center line with said first stationary gear, gearing associated with said elements to drive them, said gearing meshing with said second named stationary gear to be driven as the spider rotates.

25. In a machine of the type described, the combination of a barrel cam, a number of platens rotating there around and a revolving frame therefor, sewing machines mounted on said frame and adapted to be moved laterally on the platen by the cam, driving gears for the sewing machines, racks formed fast to the frame parallel to the direction of motion of the machines on the frame, said racks meshing with sets of driving gears to drive the sewing machines as they travel on the frame and means within said sets of driving gears to make them operable to drive in one direction of rotation only. 80 85 90

22. In a machine of the type described, the combination of a barrel cam, a platen rotating there around and a revolving frame therefor, a sewing machine mounted on said frame and adapted to be moved laterally on the platen by the cam, driving gears for the sewing machine, a rack formed fast to the frame parallel to the direction of motion of the machine on the frame, said rack meshing with a driving gear to drive the sewing machine as it travels on the frame.

55 23. In a machine of the type described, the combination of a barrel cam, a platen rotating there around and a revolving frame therefor, a sewing machine mounted on said frame and adapted to be moved laterally on the platen by the cam, driving gears for the sewing machine, a rack formed fast to the frame parallel to the direction of motion of the machine on the frame, said rack meshing with a driving gear to drive the sewing machine as it travels on the frame,

26. In a machine of the class described the combination of a number of platens linked together and adapted to travel in an endless path, means for feeding fabric intermittently to each of the platens, sewing means co-operating with said platens whereby two seams are formed at right angles to one another while the fabric is on the platen and means for discharging the finished product from the platens. 95 100

27. In a machine of the class described the combination of a number of platens linked together and adapted to travel in an endless path, means for feeding fabric intermittently to each of the platens, sewing means co-operating with said platens whereby two seams are formed at right angles to one another while the fabric is on the platen, means for severing the thread when a seam is finished and means for discharging the finished product from the platens. 105 110

28. In a machine of the class described, the combination of a rotatable frame adapted to carry fabric to be seamed, a fixed gear, a gear train on said frame moving with the frame and relatively to said fixed gear, said gear train meshing with said fixed gear and rotating, a rotatable gear on center line with said fixed gear, which rotatable gear is driven by said gear train in the direction of the frame but at a different rate of speed, a spider on said rotatable gear, sewing elements on said spider adapted to perform a seaming operation on the said fabric, said seaming operation taking place linearly at

- a rate which is less than the linear velocity of the fabric, means for making the sewing elements operable to sew, said means comprising a stationary gear on center line with 5 said first stationary gear, gearing associated with said elements to drive them, said gearing meshing with said second named stationary gear to be driven as the spider rotates, and a clutch in said gearing operable 10 from a cam, said gearing to be thrown in and out of operation when the said sewing operation is to be started and stopped.
29. In apparatus of the class described the combination of a rotatable frame, platens 15 thereon, means for feeding pieces of fabric to the platens, sewing means operable transversely of the frame to sew a lateral seam in said pieces of fabric on the platens, a barrel cam adapted to make the said sewing means 20 operable as described.
30. In apparatus of the class described the combination of a rotatable frame, platens thereon, means for feeding pieces of fabric to the platens, sewing means operable transversely of the frame to sew a lateral seam in said pieces of fabric on the platens, a stationary barrel cam adapted to make the said sewing means operable as described.
31. In apparatus of the type described a 30 shaft, a carrier revolving on the shaft, a number of platens on the carrier adapted to each carry a fabric blank, an adjacent spider revolving on said shaft, a number of sewing machine heads thereon adapted to sew seams 35 in said blanks being in number less than the number of platens, geared means for driving the carrier at a given speed, geared means between the carrier and the spider adapted to drive said spider and machines thereon, at 40 such an increased number of revolutions over those of the carrier as will permit the fewer number of machines each to register with a bag blank on a platen as the machines overtake said platens, to sew an end seam on the 45 blanks thereof.
32. In apparatus of the type described a shaft, a carrier revolving on the shaft, a number of platens on the carrier adapted to each carry a fabric blank, an adjacent spider 50 revolving on said shaft, a number of sewing machine heads thereon adapted to sew seams in said blanks being in number less than the number of platens, geared means for driving the carrier at a given speed, geared means between the carrier and the spider adapted to drive said spider and machines thereon, at 55 such an increased number of revolutions over those of the carrier as will permit the fewer number of machines each to register with a bag blank on a platen as the machines overtake said platens, to sew an end seam on the 60 blanks thereof, laterally movable sewing heads mounted on the carrier, a barrel cam stationary on the shaft, followers for said 65 cam adapted to move said last named heads laterally as described to sew longitudinal seams in said blanks.
33. In apparatus of the class described the combination of a sewing machine head, means for revolving the head about a fixed 70 axis, means for simultaneously moving said head longitudinally along said axis, said last means comprising a barrel cam and a follower for the head cooperating with an endless groove of the cam.
34. In apparatus of the class described the combination of a sewing machine head, means for revolving the head about a fixed 80 axis, means for simultaneously moving said head longitudinally along said axis, said last means comprising a barrel cam and a follower for the head cooperating with an endless groove of the cam, the motion imparted to the follower by the cam being such as to cause movement of the sewing head 85 first in one direction and then in the other, hence completing a given cycle.
35. A feeding mechanism for rotating platens comprising a driving gear, a crank lever, and shaft therefor, a connecting rod 90 connecting the gear with the lever whereby said shaft is oscillated, a frame work on said shaft adapted to oscillate with it, a grab-hook plate rotatably held on said frame, a slide rod formed therewith, a link 95 rotatably mounted on said shaft having one arm resting on the top of the connecting rod and the other of which carries rotatably a slider block for said slide rod.
36. A feeding mechanism for rotating platens comprising a driving gear, a crank lever, and shaft therefor, a connecting rod connecting the gear with the lever whereby said shaft is oscillated, a frame work on said 100 shaft adapted to oscillate with it, a grab-hook plate rotatably held on said frame, a slide rod formed therewith, a link rotatably mounted on said shaft having one arm resting on the top of the connecting rod and the other of which carries rotatably a slider 105 block for said slide rod, grab-hooks on said plate adapted to be opened by a strip at one end of their throw.
37. A feeding mechanism for rotating platens comprising a driving gear, a crank lever, and shaft therefor a connecting rod 110 connecting the gear with the lever whereby said shaft is oscillated, a frame work on said shaft adapted to oscillate with it, a grab-hook plate rotatably held on said frame, a slide rod formed therewith, a link rotatably 115 mounted on said shaft having one arm resting on the top of the connecting rod and the other of which carries rotatably a slider block for said slide rod, grab-hooks on said plate adapted to be opened by a strip at one end of their throw and adapted by means of 120 said slider-link combination to take the upward speed of a platen, then draw away 125 from the platen upwardly and then return 130

- to the other end of its stroke under action of both said slider-link mechanism and the oscillating frame.
38. Means for sewing an end seam in material comprising a rotating frame adapted to carry fabric mounted thereon, a group of rotating sewing heads moving in the same direction as the fabric at a different rate of speed, means for making the heads operable to sew during their period of passage past the fabric, said means comprising a stationary gear, gearing and a clutch associated with said heads, meshing with said stationary gear to be driven thereby as said heads rotate, a follower adapted to throw said clutch open when cooperating with a cam, and a cam adapted to cooperate with said follower during the time of passage of the head past said fabric.
39. In apparatus of the type described a shaft, a carrier revolving on the shaft, a number of platens on the carrier adapted to each carry a fabric blank, an adjacent spider revolving on said shaft, a number of sewing machine heads thereon adapted to sew seams in said blanks being in number less than the number of platens, geared means for driving the carrier at a given speed, geared means for driving said spider and machines thereon, at such an increased number of revolutions over those of the carrier as will permit the fewer number of machines each to register with a bag blank on a platen at a given loading point for the platens and to go out of register with the sewed bag blank at a given unloading point for the platens, and to catch up with the next platen at said first named point to repeat the cycle.
40. In a device of the type described, the combination of a stationary frame, a rotating frame thereon, platens on said rotating frame adapted to receive fabric blanks, sewing machines mounted on said moving frame and adapted to sew an edge of said blank laterally of the direction of motion of the blank, rotating sewing machines at the ends of the blanks adapted to sew an end seam thereon at right angles to the said seam, a switch at one corner of each platen adapted to permit passage of the laterally operable machine and then the rotatably operable machine.
41. Means for intermittently driving a revolving sewing machine comprising a stationary gear, a spider rotating with respect thereto on the same center line, a sewing machine mounted on the outer portion of said spider, gearing adapted to drive said machine and meshing with said gear and a clutch between the gearing and the machine, an arcuate cam and a follower therefor operating with said clutch at the sewing machine, said cam and follower being adapted to throw the clutch open or shut during revolution of the machine.
42. Means for intermittently driving a revolving sewing machine comprising a stationary gear, a spider rotating with respect thereto on the same center line, a sewing machine mounted on the outer portion of said spider, gearing adapted to drive said machine and meshing with said gear and a clutch between the gearing and the machine.
43. A discharge mechanism for rotating platens carrying fabric, comprising a rotating shaft, means mounted on the shaft for carrying an oscillating and revolving shaft, spring pressed means on said oscillating shaft adapted to clamp against said means mounted on the rotating shaft, means on said oscillating shaft comprising a follower, and a stationary cam adapted to operate said follower to open said clamping means as it revolves, and close said clamping means once for every revolution thereof said clamping means when open being adapted to receive a piece of fabric from one of said platens, the revolutions of the rotating shaft being directly proportional to the number of platens rotating.
44. In apparatus of the type described a shaft, a carrier revolving on the shaft, a number of platens on the carrier adapted to each carry a fabric blank, an adjacent spider revolving on said shaft, a number of sewing machine heads thereon adapted to sew seams in said blanks being in number less than the number of platens, geared means for driving the carrier at a given speed, geared means between the carrier and the spider adapted to drive said spider and machines thereon at such a different number of revolutions from the revolutions of the carrier as will permit the fewer number of machines each to register with a bag blank on a platen as the machines over take said platens, to sew an end seam on the blanks thereof.
45. In a bag sewing machine, moving platens, means for feeding folded bag blanks to the platens successively at a given point, means for sewing a lateral and an end seam in said blanks while they are mounted on the moving platens, said end seam being formed at a slower rate than the rate of travel of its blank and means for discharging said blanks from said platens.
46. In a bag sewing machine, rotating platens, means for feeding folded bag blanks to the platens successively at a given point, means for sewing a lateral and an end seam in said blanks while they are mounted on the moving platens, and means for discharging said blanks from said platens at a point beyond the said feeding point.
47. Means for moving a sewing machine on a moving frame and means for driving the machine at a rate proportional to its rate of movement, comprising a cam stationary with respect to the moving frame, a

- follower on the sewing machine cooperating with the cam, a train of gears adapted to drive the sewing machine, a rack formed fast to the frame and in mesh with one of the gears of said train, said cam being adapted to move the sewing machine on the moving frame and said rack being adapted to drive said gear train as the sewing machine moves along the rack.
- 10 48. Apparatus for sewing seams in bags comprising a rotatable frame, platens thereon adapted to carry pieces of fabric, movable sewing heads mounted on the frame adapted to sew cloth on said platens, a stationary barrel cam arranged longitudinally of the center of the frame, followers for said cam adapted to move said heads laterally of the motion of the platen as the frame moves and means for driving said heads,
- 15 20 said means comprising stationary racks on the frame and gear trains between said
- racks and said heads whereby the heads are made operable upon being driven as described and means for severing the sewing machine thread upon completion of a sewing operation.
- 16 49. Apparatus for sewing seams comprising a rotatable platen frame adapted to carry pieces of fabric, a rotatable spider driven from said frame at a relative velocity thereto, and sewing machines mounted on said spider said machines being adapted to sew a seam in said fabric in a direction parallel to the direction of frame motion and to automatically sever their threads upon completion of their seaming operations.
- 17 In testimony whereof, I have signed my name to this specification this 8th day of June, 1925.

CHARLES F. SPARKS.
